UNITED STATES PATENT OFFICE.

SAMUEL A. BULLOCK, OF PHILADELPHIA, PENNSYLVANIA, ASSIGNOR TO THE BALDWIN LOCOMOTIVE WORKS, OF PHILADELPHIA, PENNSYLVANIA, A CORPORATION OF PENNSYLVANIA.

TRUCK.

1,143,500.

Specification of Letters Patent. Patented June 15, 1915.

Application filed January 21, 1913. Serial No. 3,565.

To all whom it may concern:

Be it known that I, SAMUEL A. BULLOCK, a citizen of the United States, residing in Philadelphia, Pennsylvania, have invented 5 certain improvements in Trucks, of which the following is a specification.

My invention relates to certain improvements in trucks used under railway cars, particularly of the electric type.

10 The object of my invention is to simplify the construction of the truck at the pedestals, and to provide means for rigidly attaching the gibs in position. This object I attain in the following manner, reference 15 being had to the accompanying drawing, in which:—

Figure 1, is a side view of my improved truck; Fig. 2, is a sectional view on the line $a-a$, Fig. 1; Fig. 3, is a detached view of 20 the two gibs; and Fig. 4, is a modification of the invention, showing the cap plate secured directly to the pedestal and tie bar.

In the drawings I have shown only those 25 portions of the truck which relate particularly to my invention.

1 is the main longitudinal bar of the side frame of the truck.

2, 2 are the transoms.

3, 3 are the pedestals secured to the main 30 longitudinal bar. Each pedestal is bent, as shown, and has upper extensions 4 which are secured to the main bar by bolts 5. The lower ends 6 of the outer pedestals are bent, as shown, and are shorter than the lower 35 portions 7 of the inner pedestals, which are also bent. A tie bar 8 extends from one inner pedestal to the other, as shown.

9, 9 are cap plates which extend across the 40 opening between the pedestals, and the outer end of each cap plate is turned up, forming a flange 10 which bears against the end of the portion 6 of the outer pedestal, and there is a single bolt 11 which fastens the cap plate to this portion 6 of the pedestal. The 45 opposite end of the cap plate is of greater length than the flanged portion and the two bolts 12, 12 pass through the outer tie bar 8, the portion 7 of the inner pedestal and through the cap plate, as shown. The nuts 50 are on the under side so that the cap plate can be readily detached when the nuts are removed. The bolts 12 have a driving fit in

the tie bar and the portion 7 of the pedestal, so that these parts will be held together by the bolts even when the nuts are removed. 55

13 and 14 are the gibs, which are flanged as shown in Fig. 3 and extend on each side of the pedestals. The gib 13 has a short right angular extension 15 on its lower end which is perforated, and this portion extends between the lower portion of the pedestal 6 and the cap plate 9, the bolt 11 passing through the perforation therein. Thus the gib is held firmly in position against its pedestal and is free at its upper end in the 65 present instance, so that it is free to expand and contract. The gib 14 has an extension 16 of greater length than the extension 15 and has two perforations, and this portion 70 16 extends between the portion 7 of the pedestal and the cap plate 9 and the two bolts 12 pass through the perforations. The gib is also free at the top so that it can readily expand.

In Fig. 4, is illustrated a modification of 75 the invention, in which the right angled extensions of the flanges of the gibs 13^a and 14^a are fastened between the upper end of the pedestals and the main longitudinal bar 1 of the frame, and the cap plate 9, in this 80 instance, bears directly against the under side of the pedestals. Two bolts 12^a secure the pedestal, lower tie rod, and cap plate firmly together.

In some instances the gibs may be secured 85 both at the top and bottom.

I claim:—

1. The combination in a truck, of two pedestals having right angled extensions, the extension of the inner pedestal being of a 90 greater length than the extension of the outer pedestal; flanged gibs mounted on each pedestal and having portions located under the extensions of the pedestals; a cap plate having a flange at one end bearing 95 against the end of the extension of the outer pedestal; and bolts securing the cap plate to the pedestals and securing the gibs in position.

2. The combination in a truck, of pedestals having right angled extensions, the extensions of the inner pedestals being of greater length than those of the outer pedestals; gibs having angular portions ex- 100

tending under the pedestals; a cap plate for each pair of pedestals, the outer end of each cap plate being turned up to bear against the end of the extension of the outer pedestal; a tie bar connecting the two pedestals; and two bolts securing the tie bar, inner pedestal, gib, and cap plate together.

In testimony whereof, I have signed my name to this specification, in the presence of two subscribing witnesses.

SAMUEL A. BULLOCK.
